UNITED STATES PATENT OFFICE.

MICHAEL F. GATELY, OF WINSLOW, NEBRASKA.

ANCHORING DEVICE.

1,110,435.

Specification of Letters Patent. Patented Sept. 15, 1914.

Application filed January 23, 1913. Serial No. 743,819.

To all whom it may concern:

Be it known that I, MICHAEL F. GATELY, a citizen of the United States, residing at Winslow, in the county of Dodge and State 5 of Nebraska, have invented certain new and useful Improvements in Anchoring Devices, of which the following is a specification.

My invention relates to an improvement in anchoring devices, which while particularly useful and desirable upon the farm for anchoring the portable or traction engine used in driving the farm machinery, may be used in any situation where it is found necessary to anchor an engine or motor of any 15 character.

One object of my invention is the provision of an anchoring device which may be placed upon the ground or any surface and which will positively hold the engine in a 20 stationary position.

Another object of my invention is the provision of an anchoring device which can be instantly placed in position and quickly removed when desired; which can be adjusted to fit and receive the traction wheels or the bed of the engine; and which will be efficient, durable and cost practically nothing, all things being considered.

With these objects in view the invention 30 consists of a pair of anchoring members having at each end a prong to enter the ground or surface, and means for connecting the pair of members in parallel relation and for adjusting the members to accommodate 35 the traction wheels or bed of the engine.

The invention further consists of an anchoring device embodying novel features of construction, combination and adaptation of parts, for the desired service, substantially 40 as shown, described and particularly claimed herein.

Figure 1 is a side elevation of my anchoring device in position for use in connection with a traction engine, the wheels and driving pulley and belt only being shown and in dotted lines. Fig. 2 is a perspective view 45 of the complete anchoring device, and Fig. 3 is a sectional view through the connecting and adjusting means of the invention.

The anchoring device is designed to provide a portable, cheap and quickly applied means for securing an engine, and consists 50 of the pair of members A, which may be

made of solid bars or pipe, and one end of the members is formed with a pointed hook 55 or barb B, disposed at substantially a right angle and at their other end with a pointed hook or barb C, which is arranged at an incline, in order that when the bars are placed in position and the barbs sunk into the 60 ground or surface the bars are disposed at an incline and when pressure is brought against the cross-bar D, which connects the bars, a wedging action occurs which forces the barbs into the ground. 65

The members are arranged parallel and the wheels E, or the bed of the engine fits between the members and bears against the connecting bar the draft of the belt F, on the driving pulley serving to press 70 against the connecting bar and drive the barbs on the members deep into the ground to effect the anchoring.

The connecting bar is preferably a flat strip of metal secured to flat faces G, of the 75 bars by bolts G', and having at one end a slot H, which permits of the lateral adjustment of one of the members in order that the width between the members may be varied to suit the width of traction wheels or engine bed as circumstances require. 80

It will be apparent that I provide a device which can be adjusted to receive traction wheels or engine beds of different widths and that the device can be instantly 85 applied and removed and is thoroughly efficient and practical in every particular.

It will be understood that my anchoring device is adapted to have its members practically receive and inclose the engine, truck 90 or machine which is to be anchored, the two members being of sufficient length to permit this, and the cross piece being adjustable laterally to cause the members to bear against the machine bed or against the 95 wheels according to their width. Also, that the barbs on the members adjacent the cross piece are inclined downward and outward, which causes them when pressure is brought against the cross piece to drive the barbs 100 into the ground or surface and effectively anchor the machine in a proper manner.

I claim:

The anchoring device herein shown and described, consisting of a pair of parallel 105 bars having at one end a right-angled dis-

posed barb and at their other end an outwardly and downwardly inclined barb, and having flat faces adjacent said inclined barbs, a flat cross piece resting on said flat faces of the bars and having one end rigidly secured to one bar and its other end adjustably secured to the other bar, said cross piece engaging the structure to be anchored

and the pair of bars receiving said structure entirely therebetween.

10

In testimony whereof I affix my signature in presence of two witnesses.

MICHAEL F. GATELY.

Witnesses:

F. B. FERGUSON,
W. E. KAUFMAN.
